UNITED STATES PATENT OFFICE.

WILLIAM G. MORSE, OF PLAINFIELD, NEW JERSEY.

BILLIARD-TABLE.

SPECIFICATION forming part of Letters Patent No. 249,541, dated November 15, 1881.

Application filed October 6, 1881. (No model.)

To all whom it may concern:

Be it known that I, WILLIAM G. MORSE, of Plainfield, in the county of Union and State of New Jersey, have invented an Improvement 5 in Billiard-Tables, of which the following is a specification.

My invention is made for rendering the billiard-table more perfect, so that the playing may be more easily and accurately performed, 10 also for lessening the weight of the table and the cost of its construction, facilitating the setting up or taking to pieces and removal of the table, for preventing the accumulation of dust or moth, for allowing the table to be kept clean 15 easier than the tables heretofore made, and for permitting a much greater variety of artistic designs and ornamental work around the table and legs.

In the drawings, Figure 1 is a perspective 20 view of the table. Fig. 2 is a vertical transverse section of one side edge of the table. Fig. 3 is an inverted plan view at one corner, showing the cushion-rail and bed. Fig. 4 is a parallel perspective view of the frame-work, attaching device, and parts of the finishing attachments. Fig. 5 is a perspective view of the 25 upper end of one leg and the devices for attaching to it other portions of the frame-work. Fig. 6 is a plan of the device for connecting the leg and rails of the frame when the joints of the frame are made beveling and the legs project diagonally at the corners. Fig. 7 is an 30 inverted plan at said leg. Fig. 8 is a section of the bracket. Fig. 9 is an elevation of the 35 attaching device at an innerangle of the frame-work. Fig. 10 is a section, and Fig. 11 an elevation, of parts of the attaching device upon the leg; and Fig. 12 is a perspective view of a 40 leg with rails attached. Fig. 13 is a section, and Fig. 14 an elevation, showing the method 45 of covering the body of the frame-work of the table with broad detachable panels or fascias.

The legs B B, rails A A, cross-beams C, and center bearer, E, form the frame-work of the 50 billiard-table; the beams C rest in notched socket-pieces D, and angle-irons f are screwed to A and C to firmly connect them. The notched socket-pieces D, that receive the ends of the central bearer, E, may be provided with angle-irons screwed below the bearer E. The 55 legs B are connected to the rails A by dowels

a, Figs. 2 and 5, on the ends of the rails, passing into holes in the legs. There is also upon each leg a nut-plate, b, securely fastened; and upon each end of each rail A there is a clutch-plate, c, with a hook-shaped end, and a clamp, d; and a straining-screw, e, entering the nut-plate b, serves to draw the ends of the rails A firmly against the legs.

By reference to Fig. 4 it will be seen that 60 the hooked ends of the clutch-plates c, being acted upon by the hooked ends of the clamps d and screw e, force the dowels a firmly into the leg and cause the ends of the rails A to abut firmly against the right-angled sides of 65 the legs B; but in Figs. 6, 7, 9, and 12 the legs project diagonally, and the rails A, instead of bearing against the legs B directly, are fitted to the bearing-plates l, which are screwed to the legs B.

The bearing-plates l have beveled surfaces and stop-lugs, where the ends of the rails A bear against them, so that the rails are drawn 70 inward and made to bear firmly against the beveled surfaces of the bearing-plates l and 75 their stop-lugs.

The brackets w, Figs. 7 and 8, beneath the rails abut at their ends against the sides of the legs, as shown. This mode of fastening the legs B and rails A firmly together is cheap 80 and durable, and the table is made to stand very firmly when in use; but it can easily be taken apart for transportation.

It is to be understood that the legs B and rails A are to be connected together before introducing the cross-beams C or central bearer E.

The bed-frames L rest upon the rails A, legs B, and central bearer, E, and there are angle-irons f' screwed on the outer surfaces of the rails A and to the under sides of the bed-frames L, to hold the same firmly in place. The screws i, Fig. 4, passing through the central bearer E, also connect the bed to the parts below it.

The bed I usually make in four parts, which 95 I call the "bed-sections," each section having a slab, K, of slate or similar material, screwed to a frame, L, as usual, and in addition the cloth strips n are secured to the frames L outside the edges of the bed-slabs, to which cloth 100 strips the cloth o, which covers the bed, is nailed. There are also border-strips p, which entirely

surround the bed-sections and form a part of the bed. These border-strips are screwed to the frames L by the screws 2, so as to clamp the cloth. The bolts 3 pass through the border-strips p and strip n into the bed-slabs K, where there is a nut bedded into a hole in the stone and covered by a hard composition. The cloth may extend over the vertical faces of the strip n and bed-frames L, or it may only be attached 5 to the strip n, there being a strip of cloth along the bottom between p and L. The rest-pieces k are attached to or form a part of the border-strips. This mode of construction renders the border-strips very firm and binds the several 10 sections of the bed into one continuous whole, thereby imparting additional strength and stiffness, and insuring a permanent evenness to the bed.

The cushion-rails R are made of any ornamental character externally, and will usually 20 be made of the five strips u, u', u², u³, and u⁴. The cushion v is of any desired shape or construction. I here show it as of hollow rubber fastened to the strip u³, and the rail-cloth is 25 first secured by the strip u', and then nailed to the under side of the strip u³, in the usual way. The cushion-rails bear upon the rest-pieces k, and are firmly fastened to the bed by the bolts q', which are made to fit tightly in 30 the wood, thereby preventing the usual difficulty of the rail becoming loose or crooked by springing. The nuts of the bolts are firmly bedded in the substance of the border-strips p. The strip u³, to which the elastic cushion v is 35 attached, usually rests at its lower edge upon the top of the bed. I prefer to raise this from the bed, and also provide openings beneath the strip u³ and the elastic cushion v, as seen at t, between the border-strips p, the rest-pieces 40 k, and the rail at u⁴. The object of these openings is to allow dust to pass down freely from the bed, to prevent the accumulations of dirt and moth, and also to enable the bed to be kept clean with great facility and little wear 45 upon the cloth, as the dust can be swept outwardly on the bed and discharged downwardly below the cushions instead of being swept to the two lower corners of the bed, as usual.

I sometimes make the border-strips p thick 50 enough to fill the entire space between the cloth strip n and the rail at u⁴, and I provide holes or openings down through the substance of the border-strips, which holes may be of any desired shape or size. There may be a hole be- 55 hind each angle-mark and one at each corner. In this case the rails will bear upon the edge of the bed. I prefer the long openings and the spaces between the under side of the rail and bed, as shown.

60 The brackets F are of any suitable ornamental exterior configuration. They are adapted to form the top parts of the legs B. These brackets at the inner or back edges are hollow, and are provided each with two project- 65 ing ribs, which face each other; and the upper part of the leg is made with T-shaped ribs,

over which the brackets are passed down vertically and rest upon the upper part of the leg.

One or more intermediate brackets, G, may be applied to the rails A, there being T-shaped 70 strips screwed to such rails, and over these the brackets are passed down vertically and rest on check-blocks inside and below the T-shaped ribs.

I remark that dovetailed ribs may take the 75 place of the T-shaped ribs, if desired.

The moldings I are of such a length as to pass in between the brackets F G, and they are supported at their ends by the rest-pieces k', that project slightly from the sides of the 80 brackets. They also rest on the solid molding beneath.

The ornamental panels or fascias L' are adapt- 85 ed to fill the spaces between the moldings I and the under sides of the bed-frames L.

I provide channels in the vertical faces of the brackets F and G, for receiving the ends of these panels L'; and as it is preferable to put these panels in place after the bed has been 90 screwed to the angle-irons f', I make the channels in one side of the brackets twice the depth of the channels in the other side of the brackets, and I slip the ends of the panels into the deep channels, and then move them endwise into the shallow channels.

The ornamental angle-pieces H are applied before the bed-sections are put upon the rails A. It will readily be seen that for this detachable finish I am not confined to any particular design or arrangement of parts, but 100 can use any variety of design or style of ornamentation, the several parts of which can be loosely attached to and covered over any plain simple frame-work which is adapted for this purpose.

For plain tables I usually employ the broad 105 detachable panels or fascias L², Figs. 13 and 14, which may be mitered and clamped at the corners and more or less ornamented upon their surfaces. Sometimes I employ the brackets and the broad panel-pieces between the 110 brackets.

I remark that my improvement renders it unnecessary to employ as large slabs of slate as hitherto used, because such slabs only extend as far as necessary to properly support the ball when impacted into the cushion. This lessens the size and weight of the bed-sections. I am also able to use less cloth in covering the 115 table.

In billiard-tables it is usual to employ angle-marks upon the top of the cushion-rails. These marks are at a considerable distance behind the place where the ball strikes; hence a ball directed toward one of these angle-marks, or at any 125 imaginary point between them, will not be deflected on a line with the point calculated upon. This is a source of inaccuracy in calculating the angle of deflection and necessitates an additional element in the calculation.

I place the angle-marks y, usually upon the border-strips p, as nearly as possible at the 130

point where the ball touches the bed when it strikes the cushion, so that the angle of deflection will be as nearly as possible from the angle-mark itself. These angle-marks may be studs of ivory, or spots of paint upon the border-strips, or at the lower edge of the cushion, or they may be metallic pins, and I sometimes drive them through the cloth of the bed or rail into the wood. I prefer to attach them to the border-strips, as shown.

I claim as my invention—

1. The combination, in a billiard-table, of the legs B, broad rails A, clutch-plates c, nut-plates b, clamps d, and straining-screw e, substantially as set forth.
2. In a billiard-table, the combination, with the legs B, broad rails A, clutch-plate c, nut-plates b, clamp d, and straining-screw e, of the bearing-plates l, for the purpose and substantially as set forth.
3. In a billiard-table, the combination of the legs B, broad rails A, and notched socket-pieces D, the cross-beams C, central bearer, E, and angle-irons f', substantially as set forth.
4. The combination, with the broad rails A and the legs B, of the brackets F or G, and the T-shaped connecting-strips and the molding I, movable panels L', and angle-pieces H, for the purpose and substantially as set forth.
5. The combination, with the rails A and legs B, of the detachable panels or fascias, substantially as set forth.
6. The combination, with the rails A and legs B, of detachable brackets F and fascias or panels, substantially as set forth.
7. In a billiard-table, the combination, with the slabs K and the frames L, of the cloth strips n, substantially as set forth.

8. In a billiard-table, the combination, with the slabs K, frames L, and cloth strips n, of the border-strips p, surrounding the bed-sections, and the attaching bolts and screws, substantially as set forth.

9. The billiard-table having openings at the sides below the angle formed by the elastic cushion v, and its supporting-strip, and the bed, for the purposes and substantially as set forth.

10. The combination, with the bed, in a billiard-table, of the cushion, cushion-rail, and the rest-pieces, whereby openings are formed below the cushion, for the purposes and substantially as set forth.

11. The combination, with the bed-sections, elastic cushion, and its supporting-strips, of a strip connecting the cushion-rail and bed, having openings below the cushion, substantially as set forth.

12. The billiard-table having angle-marks beneath the line where the ball strikes the cushion and within the angle formed by the elastic cushion and the bed, substantially as set forth.

13. The billiard-table having wooden strips around the slabs outside the cloth strips and beneath the elastic cushion, in combination with the angle-marks upon such wooden strips, substantially as set forth.

Signed by me this 30th day of September, 1881.

WM. G. MORSE.
